UNITED STATES PATENT OFFICE.

ELKAN ADLER, OF NEW YORK, N. Y.

MACHINERY FOR MAKING MATCHES.

Specification of Letters Patent No. 11,405, dated August 1, 1854.

To all whom it may concern:

Be it known that I, ELKAN ADLER, of the city, county, and State of New York, have invented a new and useful Improvement 5 in Machinery for Making Wax Tapers and Matches; and I do hereby declare that the following is a full and exact description thereof.

The nature of my invention consists in 10 providing a drum around which I wind the waxed wicks, and then pass them along between grooved rollers and channels, until their ends enter separate perforations in a dipping-board, when, by means of knives, 15 they are cut into proper lengths, and thus made ready for dipping into the combustible preparation.

To enable others skilled in the art to make and use my invention I will proceed to describe its construction and operation, reference being had to the annexed drawings forming part of this specification, in which—

Figure 1 is a side-view; Fig. 2, a side central sectional view; Fig. 3, a top view; Fig. 4, end view of dipping-board; Fig. 5, side view of dipping-board with matches.

Similar letters refer to like parts.

A, frame of the machine; B, drum; C C', 30 grooved feeding-rollers; D, first grooved table; E, second grooved table; F F', knives; G, third grooved table; H, dipping-board; I, sliding-frame; J, driving-shaft; J', crank; K, crank knife shaft; L, rocking-shaft; M, driving-wheel; N, waxed-wick; a, drum-shaft; b, drum gear-wheel; c, intermediate cog-wheel; d, driving gear-wheel; e, e', roller gear-wheels; f, inner pawl-shaft; g, outer pawl-shaft; h, outer 40 pawl; i, inner pawl; j, button; k, spiral spring; l, spiral spring; m, inner pawl-shaft lever; n, outer pawl-shaft lever; o, inner button lever; p, outer button lever; q, rocking-lever; r r', racks.

The wick used for the tapers is passed 45 through molten wax and the draining-plate, in the usual manner, and then introduced upon the feeding-drum B, around which two turns are taken to prevent slipping, 50 and the end then carried into one of the grooves in the plate, D, and thence between grooved rollers C C'. Motion being communicated to the shaft, J, the driving-gear-wheel d having only a portion of its cir-

cumference cogged, sets in motion the cog-wheels e e', which being attached to the grooved rollers C C', the latter are made to revolve and draw in the waxed wicks N, and pass them onward through grooves in plate E, between knives F F', and on through grooves in plate G, until the ends of the waxed wicks enter corresponding perforations in the dipping-plate H, at which instant the cogs on d have passed the gear-wheel e' and the rollers C C' and other parts therewith connected come to a full stop; while the driving-shaft J, continuing to revolve, forces up the connecting-piece K, and with it the lower knife F' into contact with the upper knife F, severing the wicks, and leaving the short pieces fastened in the dipping-board H, as shown in Fig. 5.

Connected with K is a rocking-lever q moving on the shaft L. The pawl i is attached to the lever q by means of the shaft f. The upward movement of K consequently brings down the pawl i, and it catches in a tooth of the rack r, and on the downward return of K the pawl i and with it the sliding-frame, I, is shoved up one notch. The sliding-frame I is prevented from slipping down by the pawl h, working in rack r'. In this manner each row of waxed wicks, after having been stuck into the dipping-board, and cut to the required length, is lifted up from the grooved table G, and a new row of perforations presented, which are, in turn, filled and lifted, and so on until the dipping-board H is stuck full of matches; when it is removed from the machine and another substituted. A side view of the dipping-board H, is seen in Fig. 5. The perforations are beveled so as to cause the tapers to become slightly fastened when they are carried in by rollers C C'. When the sliding-frame I has arrived at the top of the machine, and it becomes necessary to lower it together with a new dipping-board, the button j is turned, which opens both pawls h, i, and the sliding-frame I falls to the bottom of its grooves. On releasing the button j the spiral springs k, l, cause the pawls to close again, and retain their positions against their respective racks.

The spiral spring k is connected with the lever m, on the pawl-shaft f, i being upon

the shaft *f*, the spring *k* tends to pull over *m*, and with it the shaft *f* and pawl *i*. The intermediate rod *o* unites *m* and *j*.

The spiral spring *l*, is connected with the 5 lever *n*, on the pawl shaft *g*. The spring *l*, tends to pull over *n*, and with it shaft *g*, and pawl *h*. The intermediate rod *p* unites *n* and *j*.

Fig. 5 presents a view of a dipping-board, after having been filled with tapers 10 and removed from the machine. It will be noticed that all the tapers are now of even lengths, evenly separated and properly prepared for dipping into the phosphoretic 15 compound.

The knife *F* is stationary, and does not move. The knife *F'* is bolted to the connecting-piece *K*, and moves up and down in sides grooves, as shown in Fig. 3.

20 I wind as many waxed wicks upon the drum *B* as there are grooves in the feed-rollers *C C'*, which latter being regulated according to the width of the knives, all the wicks that are drawn through are severed at one time. The waxy wicks have each two turns around the drum *B*; consequently between *B*, and feed-rollers *C C'* the wicks are held taut, as seen in Fig. 2, while the rollers *C C'* having speed proportionate 25 to motion of drum *B*, the wicks *N* are drawn in by rollers *C C'* just as fast as drum *B* delivers the same.

In the use of my invention I am not confined to making wax tapers alone. By a 30 very simple arrangement of saws and guides, I can introduce suitable strips of wood beneath the rollers *C C'*, and pass them through into the dipping-board *H*, cut and

40 deliver them in a manner substantially the same as described for my wax tapers. I can also employ other suitable material besides wood.

45 In my full-sized machines, each row of holes in the dipping-board, will hold matches enough to fill the small box, in common domestic use. Consequently at each revolution of my driving-shaft I stick a box of matches. I estimate that one person with one of my machines, can prepare 50,000 boxes of matches per diem.

50 Having thus described my invention I claim:—

1. The perforated dipping-board *H*, moved and combined with the sliding-frame I substantially as set forth.

55 2. The combination of the springs *k*, *l*; levers *m*, *n*, shafts *f*, *g*, pawls *h*, *i*, rods *o*, *p*, and button *j*, substantially as described.

3. The knives *F F'* in combination with the connecting-piece *K*, crank *J*, and lever *q*, 60 substantially as set forth.

4. The grooved rollers *C C'* in combination with drum *B*, grooved tables, *D*, *E*, *G*, and knives *F F'*, substantially as set forth.

65 5. The combination of the driving-wheel *d*, roller-wheels *e e'*, intermediate wheel *c*, and drum-wheel *b*, as set forth; the various parts of the whole machine being combined and arranged for the purpose and in the manner described, or in any other manner 70 substantially the same.

ELKAN ADLER.
